UNITED STATES PATENT OFFICE.

WILLIAM H. MUZZY, OF DAYTON, OHIO, ASSIGNOR TO THE NATIONAL CASH REGISTER COMPANY, OF DAYTON, OHIO, A CORPORATION OF OHIO, (INCORPORATED IN 1906.)

CASH-REGISTER.

1,140,476.

Specification of Letters Patent.

Patented May 25, 1915.

Application filed August 3, 1907. Serial No. 386,855.

To all whom it may concern.

Be it known that I, WILLIAM H. MUZZY, a citizen of the United States, residing at Dayton, in the county of Montgomery and State of Ohio, have invented certain new and useful Improvements in Cash-Registers, of which I declare the following to be a full, clear, and exact description.

This invention relates to improvements in cash registers, calculating machines or the like, and has more particular relation to improvements in the printing mechanism of the same.

The principal object of the invention is the provision of mechanism for printing totals on a strip, slip or check in such a manner as to clearly distinguish them from the preceding items.

A further object of the invention is to employ the regular printer controlling devices in connection with the printing of totals.

With these and incidental objects in view, the invention consists in certain novel features of construction and combinations of parts, the essential elements of which are set forth in appended claims and a preferred form of embodiment of which is hereinafter specifically described with reference to the drawings which accompany and form part of this specification.

Of said drawings: Figure 1 represents a central transverse sectional view through the type of machine shown in Patent No. 580,378, granted April 13, 1897, to J. P. Cleal and F. A. Reinhard, with my improvements applied thereto. Fig. 2 represents an end elevation of the printing attachment. Fig. 3 represents a partial rear elevation of the machine as shown in Figs. 1 and 2. Fig. 40 represents a detail perspective view of one of the selective devices for the keys used in the printing of totals. Fig. 5 represents a partial top plan view of the registering mechanism. Fig. 6 represents a detail perspective view of the printing platens and their operating cams. Fig. 7 represents a detail plan view of a portion of the record strip.

As the type of mechanism to which my improvements are applied is well known in the art, it is thought that a general description of the same will suffice. Each bank of

keys 1 controls a variable movable segment 2 which is loosely mounted upon a transverse rock shaft 3. This segment meshes 55 with a gear 4 which in turn engages a pinion 5 connected to an indicator 6 mounted upon a shaft 7. Each gear 4 also meshes with a pinion 8, see Fig. 5, which has secured to its side a smaller pinion 9, adjacent to which is a pinion 10 of the same size, that is fastened to a short sleeve 11 mounted upon a shaft 12, the pinions 8 and 9 being loosely mounted upon the said sleeve. A registering wheel 14 is also secured to the sleeve 11. Double width pinions 15, mounted in the upper ends of arms 16 which are fastened to a rock shaft 17 are arranged to be rocked into mesh with the pinions 9 and 10 and thereby couple the 65 same together, so that the registering movement of the segment 2 will be transmitted to the wheel 14 through the gear 4 and the pinions, 8, 9, 10 and 15. The pinions 15 are rocked into engagement with the pinions 75 9 and 10 by a link 18 the forward end of which is provided with a recess 19 that engages with a pin 20 projecting from the lower end of one of the arms 16, while the rear end is bifurcated and straddles a rotary shaft 21 fast to which is a disk 22 equipped with a cam groove 23 into which plays a pin 24 projecting laterally from the link 18. Any suitable form of transfer mechanism may be employed between the 80 85 wheels 14 so that the different amounts registered may be accumulated into one grand total.

It is of course to be understood that each bank of keys 1 controls a registering wheel 90 14 and connected to each wheel by the sleeve 11 is a disk 25, which is provided with a cam groove 26, into which extends a pin 27 mounted upon the upper end of a vertical rod 28. Each rod 28 is enlarged at its upper end and is provided with an elongated slot 29 through which extends the sleeve 11. This sleeve acts as a guide for the upper end of the rod while the lower end is guided by a projection 30 extending from the frame 100 31 of the machine. Near the lower end of each rod 28 is a pin 32 which enters an elongated slot 33 formed in the inner end of an arm 34. Each arm 34 is also provided at its

inner end with another elongated slot 35 through which the shaft 3 extends. A collar 36 which partially surrounds the shaft 3 is slidably mounted within the slot 35 and is held in contact with said shaft by a coil spring 37 which is interposed between one end of the slot 35 and the collar 36. This spring also keeps the other end of the slot, which is semi-circular, normally in contact 10 with the shaft 3. The outer end of each arm 34 is provided with a flange 38 which draws the keys inward as hereinafter described.

The configuration of the cam groove 26 formed in each disk 25 is such, that when the wheels 14 are at zero, each arm 34 is in the position shown in Fig. 1. As each wheel is rotated in the direction of the arrow in said figure, its disk 25 will also be rotated 20 carrying the rod 28 upwardly, which in turn, by the pin 32 and the slot 33, will lift the arm 34 so as to bring its flange 38 over one of the pins 39 projecting from the keys 1. It will be seen from the above description, that the keys 1 corresponding to the amount shown on the registering wheels 14 will be depressed when the arms 34 are cammed inwardly as hereinafter described.

The gears 4 are secured to the inner ends 30 of a series of nested sleeves 40, which carry at their outer ends type segments 41, see Fig. 2. Each segment is provided with one large and one small series of duplicate types 42 and 43 respectively, the smaller type for 35 printing the items and the larger type for recording the totals. A pair of levers 44 and 45 are pivoted upon a stub shaft 46 extending from the side frame of the machine. These levers are provided at their pivotal 40 points, with upwardly and downwardly extending arms 47 and 48 and at their forward ends each is provided with a laterally extending arm 49, which carries a rubber impression block 50, see Fig. 6. The arms 45 47 are provided with rollers 51, which are held in contact with the periphery of a cam 52 secured to one end of the rotary shaft 21, by springs 53, only one of which is shown. The shape of the cam 52 is such, that during 50 a complete revolution, the levers 44 and 45 will be moved downwardly against the tension of the springs 53, then suddenly drawn upwardly to take an impression upon a record strip 54 from the type carriers 41 and then moved slightly away from the type carriers as shown in Fig. 2. The platen lever 44 is arranged to take an impression from the item types while the lever 45 is arranged to take the totals. As both 60 levers 44 and 45 are operated upon each operation of the machine and as it is not desirable to take the total while printing the items or to print an item when the total is recorded, the following mechanism is 65 provided: A lever 55 is pivoted to the frame

of the machine and is provided with lateral extensions 56 which, when the items are being printed, lie in the path of the downwardly extending arm 48 of the total printing lever 45 and thus prevents the striking of the total types by the block 50 of the lever 45. When the total is to be recorded, the lever 55 is moved upwardly by mechanism hereinafter described, so that the extension 56 will intercept the downwardly 75 extending arm 48 of the item platen lever 44 and at the same time freeing the arm 48 of the total lever 45.

The record strip 54 is led from a supply roller 59 which is supported loosely upon a shaft 60 over guide pins 58 to the feed roller 59^a. The shaft 60 carries fast thereon a ratchet wheel 61 and a pinion 62. A plate 63 equipped with elongated slots 64 and 65 which straddle the shaft 60 of the supply roller and the nested sleeves 40 respectively, is provided with a spring pressed pawl 66 which engages the ratchet 61 and feeds the ratchet forward, when the plate 63 is moved upwardly by a cam 67 coming 80 into contact with a roller 68 secured to the upper end of the plate 63. The said plate is retracted by a coil spring 69 one end of which is secured to the frame of the machine and the other end to the plate. The cam 67 is secured to a pinion 70 loosely mounted upon the outer end of the sleeves 40 and is arranged to be rotated by an idle pinion 71 which meshes with another pinion 72 secured to the rotary shaft 21. The feed roller 59^a is provided with a gear 60^a which meshes with a pinion 61^a which in turn meshes with a pinion 117 connected to gear pinion 62 through an intermediate pinion 118. Through the train of gears aforesaid, the feed roller is thus advanced one step after each printing operation. At each operation of the machine the sliding plate 63 is reciprocated, and this through pawl 66 rotates slightly the ratchet 61, which through the gear train shown including pinions 62, 118, 117, 61^a and 60^a, serves to rotate the feeding roller 59^a. As the details are successively printed, it will be seen that each detail impression is moved through the aforesaid mechanism directly under the corresponding total types, for this reason it becomes necessary to give the strip an extra feed whenever it is desired to print a total. This additional feed is secured by a spring 100 pawl 88 secured to a reciprocating part 88 hereinafter described and which is moved only when a total impression is to be taken. It will be seen by reference to Figs. 2 and 7 that the totals are printed directly under the details but in very large bold faced type which is easily distinguished from the detail type. Further, after a total is printed, the regular feed of the strip takes place 105 and the next succeeding detail printed will 110

130

thus be two spaces below the total on account of the location of the detail type in respect to the total type. In other words, a space will be left on the strip under each total printed whereby each group of details and its total will be separated from the remaining details and totals.

A transverse shaft 73 is mounted in the lower rear portion of the machine and extends throughout the entire width of said machine. An arm 74 for each bank of keys is rigidly secured to the shaft and is connected to another arm 75 loosely mounted upon the shaft 3 by a link 76. Whenever it is desired to record the amount shown on the adding wheels 14 a handle 77 secured to one end of the shaft 73 is moved so as to rotate said shaft in the direction of the arrow shown in Fig. 1, thereby rocking the arms 74 and 75 in a similar direction. Connected to each arm 75 is a cam 78 which engages a roller 79 secured to the inner end of each arm 34 and cams the latter inwardly. As previously described, the cam disks 25, which are connected to the registering wheels 14 control the location of the arms 34, so it will be seen that as the arms 34 are cammed inwardly, they will carry the keys 1, corresponding to the amount shown on the wheels 14, with them by means of the flanges 38 and the pins 39. This movement of the shaft 73 also raises a forked shaped frame 80, see Fig. 2, by means of a cam 81 secured to the end of the shaft 73 which engages a roller 82 mounted in the lower end of the frame. This frame is guided by a projection 83 extending from the frame of the machine and is arranged to be latched in its raised position by a shoulder 84 formed upon a spring pressed pawl 85 pivoted to a prong 86 of the frame 80, engaging a projection 87 extending from the frame. The other prong 88 of the frame 80 normally lies under the lever 55 so that when the frame 80 is raised, the lever will be moved from the path of the arm 48 of the total lever 45 to in front of the arm 48 of the item lever 44. Near the end of the operation of the machine and after the printing has taken place, a lug 89 secured to the rotary shaft 21 will engage with the upper end of the pawl 85 and release the shoulder 84 from engagement with the projection 87 thereby allowing the frame 80 to return to normal position with the lever 55 in the path of the arm 48 of the total lever 45.

The amount represented by the keys 1 set up by the operation of the total crank 77 would be added upon the registering wheels 14 by an operation of the crank handle 90, but for the following mechanism: A pin 91 projecting from one of the links 76, see Fig. 1, near the end of the movement of said link toward the rear of the machine contacts with a shoulder 92 formed upon a link 93,

which is pinned at its forward end to a lever 94 and at its rear end is provided with an elongated slot 95 through which a pin 96 projects and acts as a guide for said link. As the link 93 moves rearwardly, the shoulder 92 cams a latching plunger 97 upwardly against the tension of a spring 98 surrounding said plunger, until the shoulder 92 passes beyond the plunger when the latter will spring downwardly and latch the link 93 and the lever 94 in their adjusted position against the tension of a spring 99 connected at one end to the lower lever 94 and at the other end to the front tie bar 100 of the machine. The lever 94 is secured to one end of a short pivoted shaft 101, which carries at its other end, see Fig. 2, a short upwardly extending arm 102 provided with a lug 103, which, when the lever 94 is rocked, as above described, will be brought into the path of the flange 104 secured to the side of a cam 105 fastened to the rock shaft 3. Now when the crank handle 90 is rotated, that part of the cam 105 carrying the flange 104 will be rocked downwardly, thereby through means of lug 103 and flange 104, rocking shaft 101 an additional distance, so that the upper end of lever 94, see Fig. 1, will engage with the forward end of link 18 and raise the latter so as to disconnect the slot and pin connection 19 and 20, thereby preventing the rocking of the pinions 15 to couple the pinions 9 and 10 when the link 18 is cammed forward. Near the end of the operation of the machine, a shoulder 106 formed upon a disk 107, secured to the shaft 21 will engage with a roller 108 mounted in the upper end of the plunger 97 and raise the latter to disengage its lower end from the shoulder 92 of the link 93, thereby permitting the return of the above described parts to normal position by means of the spring 99. The plunger 97 is guided in its vertical movement by a frame 109 suitably secured to the back of the machine. During this operation of the machine, the segments 2 corresponding to the banks in which keys are depressed, will be rocked until arrested by said keys. These segments as previously described engage with gears 4 which in turn mesh with pinions 5 connected to the indicators 6. It will be seen from this construction, that when the total crank 77 is actuated and the handle 90 operated, the amount represented by the keys depressed will be displayed by the indicators but will not be added upon the accumulating mechanism.

The movement of the shaft 73 toward the rear of the machine by the total crank 77, is limited by a lug 110 secured to the shaft 73 contacting with a pin 111 projecting from the machine frame, the return movement of the total crank being limited by a pin 112 with which the lug 110 contacts.

An inking ribbon 113 which surrounds the record strip is led around guide pins 114 and a felt absorbent roller 115 which is secured to a stub shaft 116 that carries a pinion 117 at its inner end. This pinion meshes with a similar pinion 118 which in turn engages the pinion 62. From this construction it will be seen that as the record strip is fed forward, the ribbon will also be moved.

10 While it is necessary to have a series of setting elements for each registering wheel employed to control the setting of the total printing types, it is not necessary where there are employed a great number of 15 wheels, that all of these setting elements should extend beyond the frame of the machine in the shape of keys.

It will of course be understood that the regular operation of the machine may give 20 the detail strip sufficient feed to equal the combined widths of the corresponding detail and total types, in which case it would not be necessary to employ the additional feed device connected to the total lever. In 25 this event, however, considerable of the detail strip would be wasted, as the details would be printed quite far apart. I therefore prefer to employ the construction shown, in which the detail amounts are 30 printed as close together as is consistent with legibility.

It is to be understood that while I have 35 show the platen levers 44 and 45 under the control of the total printing crank 77, this part of the invention is not to be limited to the printing of items and totals, but may be employed in any recording mechanism using a plurality of impression devices.

By the term "selective devices" used in 40 some of the claims, it is meant to cover broadly any means for selecting or determining the amount to be registered, indicated or recorded.

While the form of mechanism herein 45 shown and described is admirably adapted to fulfil the objects primarily stated, it is to be understood that it is not intended to confine the invention to the one form of embodiment herein shown and described, for 50 it is susceptible of embodiment in various forms all coming within the scope of the claims which follow.

Having thus described my invention what 5 I claim as new and desire to secure by Letters Patent is:

1. In a machine of the class described, the combination with an accumulating mechanism, of a printing mechanism coöperating therewith and including different distinguishable type characters, and connections for printing details and totals one below the other from said characters respectively.

2. In a machine of the class described, the combination with an accumulating mechanism, of a printing mechanism coöperating

therewith and having distinguishable detail and total types and devices for effecting the printing of the details and totals one below the other.

3. In a machine of the class described, the combination with an accumulating mechanism, of a printing mechanism coöperating therewith and having type carriers with corresponding and distinguishable detail and total printing types and devices for effecting the printing of the details and totals one below the other.

4. In an accounting mechanism, the combination of type carriers each having corresponding and distinguishable detail and total printing types, of means for taking impressions one below the other from said types.

5. In an accounting mechanism, the combination with type carriers each bearing detail and total types of different characters, of a plurality of platens operable at will for taking impressions one below the other from the detail or the total types.

6. In a machine of the class described, the combination with type-carriers having a plurality of sets of distinguishable type, of means for differentially setting the type-carriers, and means for taking an impression from any desired set of type.

7. In an operating mechanism, the combination with type carriers each having corresponding detail and total types thereon one below the other, of means for taking an impression from either the detail or total types at will.

8. In a machine of the class described, the combination with type carriers having adjacent corresponding types for printing details and totals, of means for taking impressions from either the detail or the total types, means for feeding a record material having connections whereby the printing of a total operates to leave a blank space on said record material adjacent said total.

9. In a machine of the class described, the combination with keys and a key set mechanism, of an operating mechanism, a printing mechanism and an accumulator and total printing connections whereby the keys are operated automatically to control the key set mechanism and printing mechanisms for printing the totals when desired.

10. In combination with registering devices including manually operated selective devices, a printing mechanism and total printing devices and connections, for actuating said selective devices to effect the printing of totals.

11. In a machine of the class described, the combination with a key set mechanism, of an operating mechanism, a register, a printing mechanism, total printing devices, connections whereby the key set devices are automatically operated according to amounts

on the register to print the totals; and means for throwing out the register when such totals are to be printed.

12. In a machine of the class described, 5 the combination with an accumulating mechanism, of printing type carriers, a totaling element, devices positioned by said accumulating mechanism, and having connections whereby the totaling element actuates 10 said devices, and operating mechanism for said type carriers constructed to have its extents of movement controlled by said positioned devices.

13. In an accounting mechanism, the 15 combination with a plurality of series of selective devices, of a series of type carriers controlled thereby each bearing types of different character for printing the individual items and the totals thereof, a plurality of 20 platens for taking impressions from the said type carriers and means for controlling the operation of the platens.

14. In an accounting mechanism, the combination with a plurality of type carriers 25 each bearing types of different characters and arranged to print the details and totals one below the other, of a plurality of platens to take impressions from said type carriers, and means for rendering either of the 30 platens inoperative at will.

15. The combination with selective devices, of registering and indicating mechanisms controlled thereby, an operating mechanism, a manipulative device for setting up the selective devices corresponding 35 to the amount on the registering mechanism and means for indicating this amount without adding it upon the registering mechanism.

40 16. The combination with registering and recording mechanisms, of selective devices for controlling the recording of the individual items and the totalizing of said items upon the registering mechanism, a manipulative device for setting up the selective devices corresponding to the amount on the registering mechanism and means for recording this amount in different characters from the items.

50 17. In a machine of the class described, the combination with an accumulating mechanism and printing devices, of differential mechanism for variously setting said printing devices, manipulative means for controlling said differential mechanism, totaling elements and connections actuated thereby but controlled from said accumulating mechanism for selectively operating said manipulative means.

60 18. In a machine of the class described, the combination with an accumulating mechanism, of type carriers coöperating therewith and each bearing two sets of type characters, one for details and one for totals, impression means and devices whereby the

impression means may be actuated to print from either set of type characters.

19. In a machine of the class described, the combination with an accumulating mechanism, of type carriers coöperating therewith and each bearing separate detail and total type characters, impression means, and devices whereby the impression means may be caused to print from either the detail or total type characters. 75

20. In a calculating machine, a series of rows of key bars, a printing mechanism, a calculating mechanism, means operatively connected with the calculating and printing mechanisms for drawing the key bars downwardly and causing the total of the numbers which have been calculated into the machine 80 to be printed by the printing mechanism.

21. In a calculating machine, a series of rows of key bars, a printing mechanism, a calculating mechanism, means operatively connected with the calculating and printing mechanisms for drawing the key bars downwardly and causing the total of the numbers which have been calculated into the machine 90 to be printed by the printing mechanism, and a totaling element for controlling said means. 85

22. In a calculating machine, a series of rows of key bars, a printing mechanism, a calculating mechanism, means operatively connected with the calculating and printing mechanisms for drawing the key bars downwardly and causing the total of the numbers which have been calculated into the machine 100 to be printed by the printing mechanism, a totaling element for controlling said means, and operating means for effecting the printing of the total when said totaling element is operated. 95

23. In a calculating machine, the combination of a key-board having suitably ordered numeral keys, a series of calculating wheels, means for controlling the operation of said wheels in accordance with the depressed keys, and total mechanism for automatically actuating said numeral keys in accordance with the indication of said calculating wheels. 110

24. In a calculating machine, a series of calculating wheels, means for operating the same to receive any desired entry, a key-board, having suitably ordered numeral keys, and means for automatically controlling an actuation of said keys in accordance 115 with the indication of said calculating machine. 120

25. In a calculating machine, the combination of a series of calculating wheels adapted to receive any desired entry, a key-board comprising a plurality of keys and means controlled by said wheels for automatically controlling an operation of said keys to set up the amount indicated by said calculating wheels.

26. In combination, a series of numeral wheels adapted to receive any desired entry, and key-board mechanism comprising keys controlled by said numeral wheels.
27. In a machine of the class described, the combination with numeral wheels and manipulative devices for differentially controlling the same, of a totaling element; means, rendered operative by said totaling element and controlled by said numeral wheels for controlling the operation of said manipulative devices; and type carriers positioned under the control of said devices.
28. In a machine of the class described, the combination with totalizer elements, and manipulative devices for differentially controlling the same, of a totaling element, means for controlling the operation of said manipulative devices, connections whereby said totalizer elements control said controlling means, and record mechanism positioned under control of said devices.
29. In a machine of the class described, the combination with totalizer elements each carrying a determining device, of manipulative devices for differentially controlling the operation of said totalizer elements, a totaling element; devices, set in operation by said totaling element and controlled by said determining devices, constructed to control the operation of said manipulative devices; and printing mechanism controlled by said operating devices.
30. In a machine of the class described, the combination with totalizer elements, and differential operating devices therefor, a main operating device, with means for establishing connection between said main operating device and said differential devices, a totaling element; means, set in operation by said totaling element and controlled by said totalizer elements, constructed to disconnect said main operating device and said differential operating devices; and printing devices controlled by said differential operating devices.
31. In a machine of the class described, the combination with a totalizer, of a key board mechanism comprising a plurality of keys adapted to be manually operated, and mechanism controlled by the totalizer for simultaneously operating keys to represent the total on the totalizer.
32. In a machine of the class described, the combination with a totalizer and operating devices therefor, of a key board mechanism comprising a plurality of keys adapted to be manually operated, and mechanism for simultaneously operating a plurality of said keys, the selection of the keys to be operated by said mechanism being automatically controlled by the totalizer.
33. In a machine of the class described, the combination with a totalizer and operating devices therefor, of a plurality of keys adapted to be manually operated to set up amounts to be entered on the totalizer by the operating devices, mechanism for simultaneously operating a plurality of said keys, and means controlled by the totalizer for establishing operative relation between said mechanism and the keys to be operated.
34. In a machine of the class described, the combination with a totalizer, of a key board mechanism comprising a plurality of manually operable keys, mechanism for simultaneously operating a plurality of said keys whereby to set up amounts on the key board, the keys to be operated being automatically determined by the totalizer, and means controlled by the simultaneously operated keys for printing amounts so set up.
35. In a machine of the class described, the combination with a totalizer, of a key board mechanism comprising a plurality of keys adapted to be manually operated, mechanism for simultaneously operating a plurality of said keys, the keys to be operated being determined by the totalizer, means for printing the amount represented by the simultaneously operated keys, and means for indicating said amount.
36. In a machine of the class described, the combination with a totalizer, of a key board mechanism comprising a plurality of manually operable keys, mechanism for simultaneously operating a plurality of said keys, the keys to be operated being automatically selected by the totalizer, means controlled by the simultaneously operated keys for printing the amounts so set up, and means for disabling the totalizer as an incident to printing such amounts.
37. In a machine of the class described, the combination with a totalizer element, of means for differentially operating same, a series of keys adapted to be manually and selectively operated whereby to control the movements of said differential means, mechanism for operating any one of said keys, said mechanism comprising devices differentially movable to establish a connection between said operating mechanism and the key to be operated, and means carried by the totalizer element for controlling the differential movement of said devices.
38. In a machine of the class described, the combination with a differentially rotatable element, of means for differentially rotating same, a series of keys adapted to be manually and automatically controlled for operation whereby to control the movements of said differential means, mechanism for operating said keys, and connections whereby the key to be operated is determined by the position of the aforesaid rotatable element.
39. In a machine of the class described, the combination with a series of movable totalizer elements, of means for differen-

tially moving same, manipulative devices
adjustable to set up items to be entered on
the totalizer by the operating means, and
mechanism controlled by the totalizer for
5 automatically controlling the adjustment of
said manipulative devices to set up thereon
the total on the totalizer.

In testimony whereof I affix my signature
in the presence of two witnesses.
